DESIGN FOR A BRACKET FOR SUPPORTING AN AUTOMOBILE DRIVING LAMP OR SIMILAR ARTICLE

Martin F. Rich, Bellaire, Ohio

Application December 19, 1935, Serial No. 60,178

Term of patent 7 years

To all whom it may concern:

Be it known that I, Martin F. Rich, a citizen of the United States of America and a resident of Bellaire, county of Belmont, and State of Ohio, have invented a new, original, and ornamental Design for a Bracket for Supporting an Automobile Driving Lamp or Similar Article, of which the following is a specification, reference being had to the accompanying drawing, in which—

Figure 1 is a side elevational view of a bracket, showing my new design;

Figure 2 is a front elevational view of the bracket;

Figure 3 is a top plan view of the same; and
Figure 4 is a rear elevational view of the same.

I claim—

The ornamental design for a bracket for supporting an automobile driving lamp or similar article, substantially as shown.
